UNITED STATES PATENT OFFICE.

JOHN L. PRINGLE, OF TORONTO, ONTARIO, CANADA, ASSIGNOR TO UNION MANUFACTURING COMPANY, OF NEW BRITAIN, CONNECTICUT, A CORPORATION OF CONNECTICUT.

GAGE.

No. 869,649.

Specification of Letters Patent.

Patented Oct. 29, 1907.

Application filed June 3, 1905. Serial No. 263,576.

To all whom it may concern:

Be it known that I, JOHN L. PRINGLE, a British subject, residing at Toronto, in the Province of Ontario, Canada, have invented certain new and useful Improvements in Gages, of which the following is a specification.

The object of my invention is to produce a device of the class specified having features of novelty and advantage. My particular object is to provide a tool 10 which is simple in construction and operation and is adapted for all the various purposes for which implements of this character are used.

In the drawings—Figure 1 is an end view of a device embodying my invention. Fig. 2 is a side elevation 15 partly in central vertical section. Fig. 3 is a longitudinal sectional view illustrating a modification in the construction. Fig. 4 is a transverse section on the line $x-x$ of Fig. 3. Fig. 5 is a face view of the gage head with the slides in transverse section illustrating 20 another modification in the construction.

In the embodiment of the invention shown in Figs. 1 and 2 a denotes the gage bar diametrically slotted as at e for the greater part of its length, and in this slot a slide f is suitably guided as by the tongues f' and the 25 grooves a^2 . Lengthwise of the bar and integral therewith is the eccentric a' . The head b is shaped to fit on the bar, having the eccentric b' to coöperate with the eccentric a' and is of course adjustable along the bar. It is seen that a turning movement of the head by 30 means of the coöperating eccentrics locks the head to the bar and also locks the slide in the bar.

The bar of my gage is provided at its end with marking and cutting points m , n , as shown in Figs. 1 and 2, and at the end of the slot with a point o which, in connection with a point p projecting from the inner end of the slide, forms a mortise gage. A marking point r projects from the opposite side of the inner end of the slide. It is to be noted that the two marking points, the cutting points and the mortise points project from 40 the bar in different radial planes. Thus, in this one implement four distinct and separate tools are combined and each can be used independently of the other.

The slide may be made in two pieces, as indicated in Figs. 3 and 4, so that one half t can be moved longitudinally with respect to the other half t' and to the bar.

Instead of forming an eccentric on the bar it may be made plain and one edge of the slide may project beyond the surface of the bar and be beveled off, as indicated at u in Fig. 5, while the opposite edge is cut 50 away as at u' , the binding action of the head being exerted on the slide to lock the parts together.

I claim as my invention:

1. A device of the class described comprising a gage-bar having a projecting marking point and with a longitudinal slot provided with guide ways in its inner faces, a slide 55 engaging said slot and provided with longitudinal ribs movably bearing in said guide ways and with a projecting marking point, a head adjustable longitudinally upon said bar and provided with locking means operating to lock the bar and the slide in adjusted position.

2. In an article of the character described the slotted gage-bar, the slide mounted in said slot, the head mounted on said bar, and means for locking the head and slide in any desired position of adjustment, said means comprising coöperating eccentric surfaces, one of which is carried by the head, the other being carried by the bar and fixed against rotation with respect thereto, said head being adapted for slight rotary motion with respect to the bar whereby the relative rotary movement between the eccentric parts causes them to bind the slide in the slot and the 70 head to the bar, substantially as described.

3. A device of the class described comprising a gage-bar having a projecting marking point and provided with a longitudinal slot and with a longitudinal eccentric rib, the inner faces of said slot provided with longitudinal guide 75 ways, a slide engaging said slot and provided with longitudinal ribs bearing in said guide ways and with a projecting marking point, and a head adjustably engaging said bar and with an eccentric cavity bearing over the eccentric rib of the bar.

4. In an article of the character described the slotted gage-bar provided with an eccentric surface, the two-part slide mounted in said slot, the parts of said slide being guided for longitudinal adjustment with respect to the bar and to each other, the head mounted on the bar and 85 having an interior eccentric surface which moves rotarily on to the eccentric surface of said bar to bind the slide in the slot and the head on the bar, substantially as described.

5. In an article of the character described the gage-bar provided with a projecting marking point and diametrically slotted throughout the greater part of its length, a slide mounted in and filling said slot and provided with tongue and groove guides, points projecting from each side of said slide near its inner end, one of said points coöperating with the point projecting from the bar to form 90 a mortise marking device, an eccentric integral with said bar, and the head mounted on said bar and having an eccentric opening corresponding to the eccentric shoulder on the bar to bind the slide in the slot and the head to the bar, substantially as described and for the purposes 100 set forth.

6. A device of the class described comprising a gage bar having a projecting marking point and a longitudinal slot, a slide engaging said slot and with a projecting marking point, a head adjustable longitudinally upon said bar 105 and adapted when located thereon to lock the bar and the slide in adjusted position.

In testimony whereof I affix my signature in presence of two witnesses.

JOHN L. PRINGLE.
